UNITED STATES PATENT OFFICE.

CHARLES H. LANGILL, OF BOSTON, MASSACHUSETTS, ASSIGNOR TO BOSTON AND LOCKPORT BLOCK CO., OF BOSTON, MASSACHUSETTS, A CORPORATION OF NEW YORK.

DIAPHRAGM FORCE-PUMP.

SPECIFICATION forming part of Letters Patent No. 761,591, dated May 31, 1904.

Application filed December 26, 1901. Serial No. 87,354. (No model.)

To all whom it may concern:

Be it known that I, CHARLES H. LANGILL, of Boston, in the county of Suffolk and State of Massachusetts, have invented certain new and useful Improvements in Diaphragm Force-Pumps, of which the following is a specification.

This invention relates to improvements in diaphragm force-pumps, and has for its objects to produce a very powerful, effective, easily-operated, and convenient pump which will deliver the water or other liquid being pumped at each movement of the operating handle or lever, thus causing a steady and substantially unbroken flow of such liquid from the outlet or delivery opening of the pump, and to otherwise improve the pump, as will be understood by the complete description thereof.

The invention consists of two pump-chambers, an inlet and outlet opening common to both chambers, and inlet and outlet passages from said inlet and outlet openings to said pump-chambers, with a suitable check-valve between said inlet and each pump-chamber and between each pump-chamber and said outlet, a flexible diaphragm for each pump-chamber, a yoke coupling said diaphragms together, so that their movements will be directly opposite to each other, and an operating handle or lever to alternately force each diaphragm into its pump-chamber and withdraw it therefrom.

The invention further consists in minor details of construction, arrangements, and combinations of parts, as will be fully described hereinafter, and set forth in claims hereunto annexed.

The invention is carried out substantially as illustrated on the accompanying drawings, which form an essential part of this specification, and whereon like characters of reference refer to like parts wherever they occur on the drawings.

On the drawings, Figure 1 represents a plan view of my improved pump. Fig. 2 represents a sectional side elevation of the pump looking at the outlet of the pump. Fig. 3

represents a sectional side elevation of the pump looking at the inlet of the pump. Figs. 4 and 5 represent, respectively, cross-sections of the pump on the lines 4 and 5, shown in Fig. 3. Fig. 6 represents a central longitudinal section of the pump through both pump-chambers and looking toward the inlet side of the pump. Fig. 7 represents a central longitudinal section of the pump through both pump-chambers and looking toward the outlet side of the pump. Figs. 8 and 9 represent enlarged detail horizontal sections of one of the pump-chambers, the diaphragm therefor, and the attachments to the diaphragm which causes it to move into and from said chamber, the diaphragm being shown, respectively, at its inner and outer positions on said views and showing the peculiar shape of the diaphragm, whereby its movement is very easy and the resistance thereto is reduced.

The pump consists of a casing, preferably made in one piece or casting and having the pump-chambers A and a, one of which is arranged at each end of said casing, substantially as shown. The casing of the pump is provided on one side with the inlet B and on the opposite side with the outlet C. A passage D within the casing of the pump is in open communication with the inlet and extends in both directions toward the pump-chambers. The opposite ends of this passage communicate with the passages E and e, which extend across the casing of the pump from the inlet side to the outlet side of said casing, the communication between the passage D and the passages E and e being controlled by the respective check-valves F and f, which allow of the flow of water from the passage D into the passages E and e, but prevent the return of said water to the passage D. The passages E and e are in open communication with the respective pump-chambers A and a. It will thus be seen that the passages D and E form an inlet-passage from the inlet B to the pump-chamber A, which is controlled by the check-valve F preventing the flow of water from the pump-chamber to the inlet B. It will also be seen that the pas-

sages D and e form an inlet-passage from the inlet B to the pump-chamber a, which passage is controlled by the check-valve f preventing the flow of water from the pump-chamber to the inlet. The passages E and e are in communication with a passage G, which extends in a parallel direction to the passage D, the communication between the passages E and e and the passage G being controlled by the respective check-valves H and h, which allow the free flow of water from the passages E and e into the passage G, but prevent the return of the water to the passages E and e. The passage G is in open communication with the outlet C of the pump. As the passages E and e are in open communication with the respective pump-chambers A and a, it will be seen that the passages E and G form an outlet-passage from the pump-chamber A to the outlet C, which outlet-passage is controlled by the check-valve H preventing the return of water from the outlet to the pump-chamber; also that the passages e and G form an outlet-passage from the pump-chamber a to the outlet C, which outlet-passage is controlled by the check-valve h preventing the return of water from the outlet to the pump-chamber.

The pump-chambers A and a are provided with the respective flexible diaphragms I and i, which form the outer walls of said chambers. These diaphragms are of a peculiar shape, as hereinafter described, whereby they are given a rolling movement and prevented from cramping, thus increasing the ease with which they may be operated.

A yoke J embraces the casing of the pump and reciprocates longitudinally on said casing in the direction of a line passing through the centers of both pump-chambers, so that the ends of the yoke will move toward and from said pump-chambers. This yoke is guided in its movements by means of the studs K and k on the casing and the slots j and j' in the yoke.

A lever L, pivotally attached at l to the casing of the pump, passes through a slotted perforation j' in the yoke, and said lever is preferably provided with an antifriction-roll l', which engages the sides of the slotted perforation to prevent friction between said lever and yoke when said lever is operated to move said yoke, as hereinafter described. The upper end of the lever L is provided with one or more sockets for the reception of one or more handles L'. On the drawings I have illustrated the lever L as being provided with two handles L', by which said lever may be rocked on its fulcrum l when operating the pump, as hereinafter described.

The ends of the yoke J are secured to the center of the respective diaphragms I and i by the respective bolts M and m, said ends of the yoke being located upon said bolts between two nuts M' M' and m' m' on said bolts, the inner ends of said bolts passing through per-

forations in their respective diaphragms and being provided with the cup-shaped heads or washers N n inside said diaphragms and within the pump-chambers, which cup-shaped heads or washers form followers to support the diaphragms during their movements when the pump is operated, as will be understood by the complete description of the pump.

Upon the bolts M and m between the diaphragms I and i and the nuts M' and m' are placed the respective sleeve-washers O and o, the inner ends of which are provided with the cup-shaped heads or washers P and p, resting against the outside of the diaphragms and forming followers to support the diaphragms during their movements when the pump is being operated.

From the above description of the device it will be seen that when the lever L is rocked upon its fulcrum it will cause the reciprocation of the yoke J upon its guides on the pump-casing and that the reciprocation of the yoke through connections with the diaphragms will cause the alternate forcing of the diaphragms into and the withdrawal of the diaphragms from the respective pump-chambers A and a, the diaphragm attached to one end of the yoke being forced into its pump-chamber, while the diaphragm attached to the other end of the yoke is withdrawn from its pump-chamber, or vice versa. It will also be seen that this alternate forcing of the diaphragms into and withdrawal from their pump-chambers will cause the alternate filling of the pump-chambers through the inlet-passages therefor and the discharging of the contents of said pump-chambers through the outlet-passages therefor; also that the check-valves in said passages will prevent the return of the water through said passages. By this alternate operation of the diaphragms at opposite ends of the pump-casing it will be seen that substantially a continuous flow of water will be maintained without employment of an air-chamber.

In order to prevent the accumulation of sand, gravel, or other materials in the lower part of the pump-chambers near the diaphragms, which would be liable to cut or otherwise wear or destroy the diaphragms, I prefer to cut away a portion of the wall of the pump-chambers between the pump-chambers and the respective passages E and e, substantially as shown at Q and q, thereby forming a free passage between the lower portions of the pump-chambers and said passages, which will be substantially on a level with the lower portions of the pump-chambers, and consequently there will be no pockets formed in the lower portions of the pump-chambers to collect the sand and gravel which may enter the pump with the water being pumped.

In order to inspect, insert, or to renew the valves F, f', H, and h, I provide the casing of the pump with the respective caps or plugs F', f', H', and h', which are easily removed

from said casing, and when removed they leave the valves exposed.

On the drawings the check-valves have been shown as being ball-valves, which in many respects is the preferred form in which to use said valves; but it will be understood that any common form of puppet or flat-clapper valves might be substituted for the ball-valves shown without departing from this invention.

10 When the check-valves are made in the form of ball-valves, I provide the casing of the pump with the depending fingers or pins E' e' and G' g', which are placed so as to prevent the respective valves F, f, H, and h from being moved from their proper positions relative to their valve-seats in the casing by the flow of water through the passages controlled by said valves.

From the above description of this construction of my improved pump it will be seen that the same is very simple in construction, is very effective in operation, and being formed with the inlet and outlet passages, as well as the pump-chambers and valve-seats, in a single casting can be made at a very slight expense, as there is but a very slight amount of finishing to be performed upon the rough casting of the casing of the pump.

Heretofore in diaphragm-pumps the diaphragm has been so shaped that it formed a truss in itself and when moved from an inner to an outer position, or vice versa, as when pumping water, has to be upset or crimped in order to be able to overcome the truss which it forms in itself and to pass its central position in moving in either direction. It consequently requires the expenditure of considerable force to move the diaphragm from one end of its stroke to the other end even when no water is being pumped. It is one of the principal objects of my present invention to overcome this loss of power in moving the diaphragm, and this I accomplish by the peculiar shape of the diaphragms, whereby they are given a rolling or swinging movement upon themselves when making their inward and outward movements. The outer rims of the diaphragms are clamped to the outer edges of the pump-chambers by means of the respective rings R and r and the screws or bolts S and s, which act to hold the rims of the diaphragms firmly between said parts. The normal position and shape of each diaphragm is that which it occupies when withdrawn from its pump-chamber to its outer position and is substantially that illustrated by a sectional view in Fig. 9. In this position the portion 10 of the diaphragm which is just inside the rim clamped by the ring R is bent inward toward the pump-chamber, as shown in said Fig. 9. The next inside part 11 of the diaphragm is curved toward the outside of the pump-chamber and continues until it meets the main curved portion 12 of the diaphragm.

By this construction of the diaphragm it will 65 be seen that when pressure is applied to the center of the diaphragm, tending to force the diaphragm into the pump-chamber, its outer portion 10 will yield, and therefore allow the portion 11 to turn or roll gradually upon 70 itself, causing the curve of the curved portion 10 to gradually move toward the center of the diaphragm, assuming the position of said parts as shown on Fig. 8 and until the diaphragm has reached its central position, when 75 a further and complete inward movement will cause the diaphragm to assume substantially the shape illustrated in Fig. 8 and with the parts 10, 11, and 12 substantially as shown. The reverse movement of the diaphragm will 80 cause substantially the same action on the various portions thereof and until the diaphragm reaches the position shown in Fig. 9. By this movement of the parts of the diaphragm it will be seen that very slight power will be required to operate it as compared with the diaphragm now in common use.

Having thus fully described the nature, construction, and operation of my invention, I wish to secure by Letters Patent and claim— 90

1. A flexible diaphragm for a diaphragm-pump having an outer annular flat clamping-rim, a central portion concaved on one surface and correspondingly convex on the opposite surface, the concavo-convex central portion connected to the rim by combined concave and convex surfaces on opposite surfaces of the diaphragm which extend through and on opposite sides of the plane of the clamping-rim, thus forming a flexible hinge upon 100 which the diaphragm turns when being contracted or expanded.

2. In a diaphragm force-pump, the pump-chambers A and a, at opposite ends of the pump, the cross-passages E and e each communicating with said pump-chambers, the inlet B, the longitudinal passage D in open communication with said inlet, the valves F and f controlling communication between the passage D and the respective passages E and e, 110 the discharge C, the longitudinal passage G in open communication with said discharge, and the valves H and h controlling communication between the respective passages E and e and the longitudinal passage G, combined 115 with the flexible diaphragms I and i on the respective pump-chambers A and a, the yoke J connecting said diaphragms, the lever L and its handles L' passing through a perforation in said yoke and pivoted to the pump, and the 120 antifriction-roll l' within perforation in said yoke.

In testimony whereof I have affixed my signature in presence of two witnesses.

CHARLES H. LANGILL.
